EXTRUDING MACHINE

Vernon E. Royle, Paterson, N. J.

Application June 25, 1935, Serial No. 28,229

7 Claims. (Cl. 146—174)

This invention relates to an improvement in extruding machines and has for an object to provide a strainer head which is adapted for thorough and expeditious operation upon materials of varying characteristics, and which includes an improved means for adjusting, cleaning and replacing the parts and assembling them in operative position, as well as for disassembling the same.

Another object consists in providing a strainer head divided transversely into two members hinged together and having mechanically operated means for quickly locking and unlocking the members in the head.

Another object consists in providing a strainer head having means mounted on the movable member for cutting the material transversely, when so desired, after it has passed through the head, which cutting means is fixedly mounted at its outer extremity to extend diametrically across the line of extrusion and actuated by a motor.

Another object consists in certain improvements in the form, construction and arrangement of the several parts whereby the above named and other objects may effectively be attained.

Machines of this character are designed to operate during the process of reclaiming the rubber, upon rubber compounds that include various substances, and these substances vary greatly in consistency and individual characteristics. Consequently, it is necessary to provide a strainer head which is not only strong and effective, but which may be rapidly assembled and disassembled, and rendered proof against serious injury arising from an unusual strain due to the presence of some foreign matter undergoing the operation.

A practical embodiment of my invention is represented in the accompanying drawings, in which

Fig. 1 represents a front elevation of a head of an extruding machine having my improved means applied thereto;

Fig. 2 represents a plan view of the same;

Fig. 3 represents a vertical section taken in the plane of the line III—III of Fig. 2, looking in the direction of the arrows;

Fig. 4 represents a similar view with the parts shown in another position;

Fig. 5 represents a vertical section taken in the plane of the line V—V of Fig. 1, looking in the direction of the arrows;

Fig. 6 represents a detail horizontal section

taken in the plane of the line VI—VI of Fig. 3, looking in the direction of the arrows; and

Fig. 7 represents a detail horizontal section taken in the plane of the line VII—VII of Fig. 5, looking in the direction of the arrows.

The cylinder of the extruding machine, of which the front portion only is shown, is denoted by 1 and its bore liner by 2. The usual stock screw or plodder 3 is housed within the liner 2 of the cylinder and projects therefrom for cooperation with the fixed member 4 of the strainer head. This fixed member 4 is secured in position on the cylinder 1 by means of a series of stud bolts 5 which extend outwardly from the cylinder and register with holes in the face plate 6 of the member 4. Nuts 7 are provided for threading on the bolts 5 in order to secure the face plate 6 and hence the member 4 in position on the cylinder. The member 4 includes a liner 8 which is shouldered at 9 to register with a reduced flange 10 that projects forwardly from the bore liner 2, as shown in Fig. 5. A suitable washer 11 is disposed between the cylinder 1 and the bore liner 2 on one hand and the face plate 6 of the member 4 on the other hand.

Suitable passages 12 are disposed in the member 4 for the circulation of a temperature controlling medium in a manner well understood in the art. The interior of the member 4 immediately in advance of the liner 8 expands or flares abruptly to a shoulder 13, in which flared chamber the free end of the stock screw accuates.

The movable member of the head is denoted by 14 and has its inner circumference 15, for a short distance, substantially equal to the inner diameter of the shoulder 13 of the fixed member 4, then it is flared forwardly and outwardly at 16, though its flare is not as abrupt as that of the interior of the fixed member 4 between the end of the liner and the shoulder 13. The movable member 14 has also formed on its inner circumference 15, 16 vertical partitions 17, 18 and connecting horizontal partitions 19, 20, which serve to divide the material passing therethrough into four sections. Each partition is tapered inwardly at 21, thence outwardly at 22 to allow the plastic material to be freely extruded.

The inner surface of the movable member 14 is recessed at 23 for the reception of a relatively thin foraminous plate 24, the perforations in which are denoted by 25. This plate 24 is secured in position in the recess 23 by screws 26 and arranged to abut the vertical and horizontal par-

titions which prevent the plate from buckling or becoming distorted by the action of the material being forced away from the stock screw.

A screen or strainer 27 is interposed between the shoulder 13 and the plate 24 when the members 4 and 14 are assembled.

The member 14 is adapted to be swung into and out of engagement with the member 4 by means of a hinge formed by trunnions 28, 29 on the arm 30 which extends outwardly and forwardly on the side of the fixed member 4, and similar trunnions 31, 32 are formed integral with the arms 33, 34, respectively, on the movable member 14. Trunnions 28, 29, 31, 32 are arranged in vertical alignment so as to receive a hinge pin 35 journaled therein.

The movable member 14 is removably secured to the fixed member 4 by means of an annular ring 36 formed of a pair of segments 37, 38 secured together by bolts 39, 40. This annular ring 36 has an interior annular flange 41 on its rear transverse face, which is arranged to oscillate in a peripheral groove 42 in the outer end of the member 4, as shown in Fig. 5. The outer transverse face of the ring 36 is provided with a series of interior radial projections 43 which are designed to mate with a series of exterior radial projections 44 formed adjacent the inner transverse face of the movable member 14. These projections 43, 44 have their sides cut on radial lines and the projections 44 are of such size and form that they can pass between the projections 43 on the ring 36, as clearly shown in Fig. 4. This construction enables the movable member 14 to be swung toward and away from the fixed member 4, during which movement the projections 44 will pass between the projections 43 on the ring 36.

In order to conveniently actuate the ring 36 so that the projections 43 may be brought into and out of overlapped relation with the projections 44 on the member 14, I provide a hand operated mechanism comprising a bracket 45 secured to the fixed member 4 at 46 (see Fig. 5), a drive shaft 47 journaled in the bracket, a worm 48 fast on the drive shaft, and a worm wheel 49 coaxing with said worm and secured on a shaft 50 also journaled in the bracket at right angles to the drive shaft 47, on which shaft 50 is fixed a pinion 51 arranged to mesh with a rack 52 fast on the segment 38 of the ring 36.

To rotate the shaft 47 to actuate the parts, a hand wheel 53 is fixed on the shaft 47 and provided with a handle 54. If desired, the hand wheel 53 may be rotated by means of a bar (not shown) which may be inserted in sockets 55 arranged in the periphery of the hand wheel 53. Thus, it will be seen that if the hand wheel 53 is moved in the direction of the arrow shown in Figs. 1, 2 and 3 to rotate the shaft 47, the worm 48 which is mounted on the shaft will actuate the worm wheel 49 which, in turn, will move its shaft 50 upon which the pinion 51 is fixed, and, as the pinion is in engagement with the rack 52 fast on the segment 38 of the ring 36, it will be moved to the position shown in Fig. 4. In this position the projections 43 are located between the projections 44 and the member 14 free to be swung outwardly away from the member 4 to the position shown in dotted outline in Fig. 2.

In order that the screen 27 and foraminous plate 24 carried by the movable member 14 will be brought into intimate contact with the shoulder 13 of the fixed member, each of the surfaces 75 of the projections 43, 44, which contact by the

rotation of the ring 36, is provided with a slight inclination, so that, as the projections 43 are slid onto the projections 44, a wedge-like action takes place and the member 14 will be moved longitudinally toward the fixed member 4. To compensate for wear and adjustment of the contact surfaces of the projections 43, 44, I provide each of the projections 43 with a wear-resisting metal plate 56 secured thereto by cap screws 57, while each of the projections 44 has a similar plate 58 secured by cap screws 59.

The device for cutting the extruded material transversely at predetermined intervals comprises a bar 60 extending diametrically across the end of the member 14 and provided at its outer extremities with plates 62, 63 secured to a ring gear 64 fitted to rotate in an annular recess 65 in the outer end of the movable member 14. This ring gear 64 is maintained in position by a retainer ring 66 secured to the member 14 by screws 67. The bar 60 is also provided with a centrally disposed hub 68 which is fulcrumed on a pin 69 having its inner end screwed into the junction of the vertical and horizontal partitions 17, 18, 19, and 20, respectively, while the outer end is arranged to receive a collar 70 pinned thereto at 71. This bar 60 is further provided with blades 72, 73 having their cutting edges disposed in opposite directions, so that, when the ring gear 64 is rotated in its recess 65, the blades 72, 73 will move in opposite arcuate directions around the pin 69.

The ring gear 64 is controlled and actuated by a chain 74 which receives its motion from a pinion 75 fast on the shaft 76 of an electric motor 77 mounted on a bracket 78. This bracket 78 is arranged to receive the upper end of the hinge pin 35 and is secured to the trunnion 31 of the arm 30 on the movable member 14 by dowels 79 (see Fig. 3). Thus, it will be seen that the bracket 78 with its motor and adjacent mechanism will be maintained in operative position whether the members of the head are in open or closed position and will be moved on the hinge pin with the movable member 14.

In operation: The material to be strained, such, for instance, as masticated old rubber products and the like, is urged forwardly by the stock screw 3 into the flared chamber in the fixed member 4 of the head, then through the screen 27 and holes 28 in the plate 24, and then through the flared outlets in the movable member 14 where it is divided longitudinally into four sections by the vertical and horizontal partitions. The passage of the material from the stock screw 3 into the adjacent chamber is more rapid than its movement from the plate 24 into the divided outlet because of the obstruction provided by the plate. The provision of the abruptly flared chamber at the end of the screw and the less abruptly flared outlet conform the device to this condition. Additionally, the fact that the screen is of much greater cross sectional area than the screw receiving portion tends to increase the output of the device by permitting the screw 3 to work out or near its capacity instead of hampering it by back pressure on the material. After a certain amount of material has been strained, it may be found desirous to clean or remove the screen or plate, and, in order to bring the same to a position to be operated upon, the hand wheel 53 is rotated in the direction of the arrows shown thereon in Figs. 1, 2, and 3, which rotation actuates the shaft 47 having the worm 48 thereon, which rotates the worm 7.

wheel 49 fast on the shaft 50 carrying the pinion 51 that meshes with the gear segment 52 fixed on the ring 36. When the ring 36 has been moved to the position as shown in Fig. 4, the projections 43 will have been moved to register with the spaces between the projections 44 on the movable member 14.

With the projections 43, 44 out of contact with each other, the movable member 14 is free to be swung on its hinge pin 35 to the position shown in dotted outline in Fig. 2. In swinging the movable member 14 away from the fixed member 4, the full surfaces of the screen 27 and plate 24 are exposed, so that any cleaning or removal which may be required is readily and easily accomplished. After the screen and plate have been cleaned or renewed and returned to their former positions, the movable member is again swung on its hinge pin into engagement with the fixed member 4 and the hand wheel 53 manipulated so that the shaft 47, together with the worm 48, worm wheel 49 and shaft 50, will actuate the pinion 51 and cause it, by engagement with the segment 52, to rotate the ring 36, which, in turn, brings the plates 56 on the projections 43 slidably into contact with the plates 58 on the projections 44 of the movable member 14. With the inclined surfaces of the plates on the projections fully in contact, the movable member 14 will be locked to the fixed member 4 and the parts again placed in condition for further operation.

When desired, the material extruded from the outlets in the movable member may be cut transversely into predetermined lengths by the blades 72, 73 on the rotatable bar 60. To actuate the bar, the motor 77 is energized and the pinion 75 rotated to drive the ring gear 64 through the chain 74, to which ring gear the plates 62, 63 at the outer ends of the bar 60 are secured.

Thus, it will be seen that the operative force or movement of the ring gear 64 acts upon the ends of the bar 60, moving the blades 72, 73 in opposite arcuate directions and about the pin 69 located at the junction of the vertical and horizontal partitions, thereby effecting a smoothness and celerity in the performance of the cutting operation.

The construction above described enables the members forming the strainer head to be transversely separated and replaced in an expeditious manner, while the readjustment of the parts in the exactly desired positions is readily assured.

It will be understood that various changes may be resorted to in the form, construction and arrangement of the several parts without departing from the spirit and scope of my invention, and hence I do not intend to be limited to the details herein shown and described except as they may be included in the claims.

What I claim is:

1. In a machine for extruding plastic material in a straight line, the combination of a head housing a stock screw, a member hinged to swing into and out of engagement with said head, said member being provided with exterior radial projections on its inner end, an annular device rotatable on said head and provided with interior radial projections on its inner periphery arranged to engage said exterior projections on the swinging member, and means for actuating said annular device for moving said interior projections into engagement with the exterior projections for locking the member to the head.

2. In a machine for extruding plastic material

in a straight line, the combination of a head housing a stock screw, said head being provided with an annular groove adjacent its outer end, a member hinged to swing into and out of engagement with said head, said member being provided with exterior radial projections on its inner end, an annular device rotatable in said groove in the head and provided with interior radial projections on its outer end arranged to engage said exterior projections on the swinging member, and means for actuating said annular device for moving said interior projections into and out of engagement with the exterior projections for locking and unlocking the swinging member to
